[57] CLAIM

The ornamental design for an endoscope, as shown and described.

DESCRIPTION

FIG. 1 is a front, right side and plan perspective view of an endoscope, showing my new design;

FIG. 2 is a bottom, left side and rear perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and

FIG. 8 is a bottom view thereof.

Portions of the endoscope tube have been broken away for convenience of illustration only.

FIG. 1

FIG. 2

FIG. 3

FIG. 4

FIG. 5
